UNITED STATES PATENT OFFICE.

FRANCIS A. PETER, OF WASHINGTON TOWNSHIP, LEHIGH COUNTY, PENNSYLVANIA.

SNOW GUARD OR FENDER.

SPECIFICATION forming part of Letters Patent No. 706,684, dated August 12, 1902.

Application filed May 16, 1902. Serial No. 107,658. (No model.)

To all whom it may concern:

Be it known that I, FRANCIS A. PETER, of Washington township, in the county of Lehigh and State of Pennsylvania, have invented certain new and useful Improvements in Snow Guards or Fenders; and I hereby declare that the following is a full, clear, and exact description thereof, reference being had to the accompanying drawings, which form part of this specification.

This invention is an improved snow guard or fender for use on roofs, its object being to provide a simple, strong, and neat guard which can be readily applied to slate or shingle roofs; and it consists in the novel construction of the guard hereinafter described and claimed, and illustrated in the accompanying drawings, in which—

Figure 1 is a perspective view of the complete guard; Fig. 2, an enlarged longitudinal section therethrough, and Fig. 3 an enlarged front view of the guard-plate. Fig. 4 is a detail sectional view of a slight modification of the guard.

The device comprises a guard-plate A and a fastening-bar B. The guard-plate stands transversely of and perpendicular to the bar and is preferably of ornamental foliated design and provided with a notch *a* at bottom to fit over the bar B, and on its front side just above the notch is an abutment C, the lower end of which rests on top of the bar B and forms a brace for the plate. This abutment is also shown as provided with a pintle *c* on its lower end, which fits into a hole *b* in the bar B and may be riveted thereto, thereby firmly uniting the plate and bar. Where the parts are to be riveted together, the guard-plate should be made of malleable or wrought metal. Above the upper end of abutment C the guard-plate A is provided with a projecting flange or shoulder D, under which (between it and the upper end of abutment C) the extremity of the upturned end B' of bar B is fitted.

As shown, the fastening-bar B extends beyond the front of the guard-plate and is then bent backwardly at an angle upon itself and toward the guard-plate, as at B', thus forming a stiffening-brace for the guard-plate, which will relieve the pintle *c* and prevent

the snow or ice breaking the guard from the bar. The portion of the bar projecting beyond the inner face of guard-plate is perforated, as shown, for the passage of fastening 55 nails or screws, by which the guard may be attached in any desired position or place on a roof or wherever the guards are to be used.

The construction of the invention is perfectly obvious from the drawings and further 60 explanation is unnecessary; but I do not wish to confine myself to any particular size or dimension of parts, nor to any particular ornamental configuration of the guard-plate, nor to restrict the invention solely for use as a 65 snow-guard.

In Fig. 4 the brace B' is formed of a separate piece of metal riveted to the outer end of bar B instead of being formed integral therewith. This obvious modification I consider within the scope of my invention.

Having thus described my invention, what I therefore claim as new, and desire to secure by Letters Patent thereon, is—

1. In combination, the fastening-bar having 75 one end bent backwardly upon itself to form a brace, and a plate arranged perpendicular to and transversely of the bar, and abutting against the extremity of the brace, said plate having a notch to accommodate the bar and secured thereto, substantially as described.

2. In combination, the guard-plate having an abutment on its front side and a notch in its lower edge; with a fastening-bar lying 85 transversely of the plate, and extending through the notch therein, and having its front end bent backward to form a brace, the extremity of which is fitted against the plate above the abutment, substantially as described.

3. A snow-guard, comprising a fastening-bar having one end bent backwardly upon itself at an angle, and a plate lying transversely of the bar, having an abutment provided with a pintle engaging an aperture in the bar, and a flange above the abutment the extremity of the brace being confined between the flange and top of abutment, substantially as described.

4. A snow-guard comprising a plate having an abutment, provided with a pintle to se-

cure it to the fastening-bar, a fastening-bar extending under and at right angles to the plate, and a brace between the front end of bar and the plate, substantially as described.

5 5. A snow-guard comprising a fastening-bar, a plate lying transversely of the bar having an abutment resting on the bar and a flange above the abutment, and a brace between the front of plate and front end of bar,

substantially as and for the purpose set forth.

In testimony that I claim the foregoing as my own I affix my signature in presence of two witnesses.

FRANCIS A. PETER.

In presence of—

G. T. OPLINGER,
FRANK N. PETER.
